FIG. 4

INVENTOR.

KAZIMIRZ GALESKI

BY *George C. Heinrich*

ATTORNEY.

UNITED STATES PATENT OFFICE.

KAZIMIRZ GALESKI, OF HARRAH, OKLAHOMA.

SHIP-SALVAGE DEVICE.

1,352,950.

Specification of Letters Patent. Patented Sept. 14, 1920.

Application filed December 30, 1919. Serial No. 348,269.

To all whom it may concern:

Be it known that I, KAZIMIRZ GALESKI, a citizen of Poland, residing at Harrah, county of Oklahoma, and State of Oklahoma, have invented certain new and useful Improvements in Ship-Salvage Devices, of which the following is a specification.

This invention relates to a device for raising and salvaging sunken ships and it has 10 for an object to provide a simple arrangement whereby an adequate lifting power may be exerted and the ship safely supported when raised as long as may be desired either for repairs or otherwise. 15 A further object is to provide a device of this kind which will constitute in effect a closed dock in which the ships may be contained and which may be opened when desired to permit of the passage of the ship 20 therefrom.

For further comprehension of the invention, and of the objects and advantages thereof reference will be had to the following description and accompanying drawings, and to the appended claim in which the various novel features of the invention 25 are more particularly set forth.

Figure 1 of the drawings is a side elevation of the device showing it connected to a 30 sunken ship to raise the latter.

Fig. 2 is a plan view of the device on a larger scale.

Fig. 3 is an end view thereof.

Fig. 4 is a transverse vertical section on 35 the line 4-4 of Fig. 2.

As shown in the drawings my ship raising and salvaging device comprises a hollow rectangular pontoon or float made up of two sections or halves consisting of the 40 main side members 1 and 2 from the ends of which the inward offsets 1' and 2' project toward one another, their end faces meeting in the median line of the pontoon, the offset members at one end being hinged together 45 as at 3 so as to enable the two halves or sections to swing apart. The offset members at the opposite end of the pontoon are locked together by suitable releasable locking means which here consists of a series of 50 pins 4 projecting rigidly from the offset 2' and projecting into suitable apertures in a series of arms 5 fixed to a vertical shaft 6 journaled in brackets on the offset. The shaft 6 has a spur gear 7 fixed on the upper 55 end thereof which is adjacent the top or floor of the pontoon, this gear having mesh-

ing therewith a pinion 8 on a vertical stub shaft 9 suitably journaled on the top of the pontoon and provided with a handle wheel 10. As will be apparent from the above description, and as shown in Fig. 2 of the drawings, the pontoon comprises a rectangular structure inclosing an opening or space 12 within the members thereof, into which opening the ship is adapted to be drawn when raised.

The ship is adapted to be raised by suitable chains or cables which are secured thereto or passed around the bottom thereof by divers let down from the pontoon, these 70 cables being connected to winding devices on the pontoon. As here shown there are a series of four of these winding devices located on the pontoon adjacent the four corners of the central space or opening. A 75 pair of cables 13 and 14 may thus be passed under the front and rear ends of the ship as indicated in Fig. 1 where the ship is shown at 15 suspended in the cables, whose ends are connected to the winding devices on opposite 80 halves or sections of the pontoon.

These winding devices each comprises a drum 16 journaled in brackets 17 on the pontoon and each having a gear 18 fixed on one end of the drum shaft, which gear is 85 engaged by a pinion 19 on the shaft of an electric motor 20. The opposite end of each drum shaft has fixed thereto a ratchet wheel 21 engaged by a pawl 22 pivoted as at 23 in a bracket 24 on the pontoon and normally 90 pressed against the ratchet wheel by a spring 25, the pawl being releasable by a foot pedal 26. Fixed on the pontoon are a pair of standards 27 having pulleys 28 rotatably carried in their upper ends, these pulleys partially overhanging the side edges of 95 the central opening.

The ends of the ropes are passed upward over these pulleys and secured to and wound upon the drums. It is to be understood of 100 course that the pontoon will be equipped with suitable means for supplying power to the motors 20.

In use the pontoon is positioned over the sunken ship with the bow of the ship toward 105 the end thereof which is adapted to open. The cables 13 and 14 are then attached to the ship and the motors are then started, causing the cables to wind upon the drums, and raise the ship. When raised, repairs 110 can be made to the ship sufficient to allow it to be floated out of the pontoon the two

halves being swung apart on the hinges 3 to permit of the ship passing out of the enclosed space.

Having thus described my invention 5 what I claim as new and desire to secure by Letters Patent, of the United States is as follows—

A ship raising device comprising a rectangular pontoon separated along its median line into two sections and inclosing a rectangular space, said sections being hinged together at one end, releasable means locking the other ends of the sections together,

said means comprising brackets on said sections, a vertical shaft journaled in said brackets, a series of arms fixed to said shaft and provided with apertures, a series of pins adapted to engage the apertures of said arm, a spur gear on said shaft, and a pinion in mesh with said spur gear and adapted to be 15 operated by a hand-wheel on the vertical stub shaft on said pinion, and means adapted to raise the ship into the said space.

In testimony whereof I have affixed my signature.

KAZIMIRZ GALESKI.
